DISPENSING MACHINE

Luther D. Dennis, Comanche, Okla.

Application February 14, 1939, Serial No. 256,352

2 Claims. (Cl. 312—48)

This invention relates to new and useful improvements in dispensers and more particularly to a dispensing machine especially adapted for dispensing bottled beverages and in fact, other articles of a cylindrical nature.

The principal object of the present invention is to provide a dispensing machine whereby articles can be dispensed in a safeguarded and fool-proof manner with a minimum amount of mechanism.

Another important object of the invention is to provide a coin-controlled dispensing machine which while being of simple construction will eliminate the dispensing of the goods without coin actuation.

Still another important object of the invention is to provide a dispensing apparatus of the character stated, wherein the goods can be replaced in a convenient manner as the supply in the machine diminishes.

These and other objects and advantages of the invention will become apparent to the reader of the following specification.

In the drawings—

Figure 1 represents a vertical sectional view through the mechanism of the machine.

Figure 2 is a front elevational view with the shell removed.

Figure 3 is a horizontal sectional view taken substantially on line 3—3 of Figure 2.

Figure 4 is a sectional view taken substantially on a line 4—4 of Figure 2.

Figure 5 is a vertical sectional view taken substantially on line 5—5 of Figure 1.

Referring to the drawings, wherein like numerals designate like parts, it can be seen that numeral 5 represents a base from which rises rear uprights 6, bridged by a bar 1, just below the upper ends thereof. At the forward end of the base 5 are inner uprights 8 and outer uprights 9. Adjacent inner and outer uprights 8—9 are connected by a wall or plate 10. The upper ends of the uprights 8 are bridged by a bar 11 which supports the forward end portion of a chute section 12. A lower chute section 13 inclines from its lower discharge end 14 passing through the front of the shell 15 to the upwardly curved end wall 16. Side flanges 17 of the chute section 13 merge with side walls 18 extending forwardly from the back wall 16, and to the side walls 18 are pivotally secured as at 19, flanges 20 extending upwardly from the intermediate chute section 12, the forward end portion of which rests on the bar 11. The forward end portion of the chute 12 is shaped to form an upwardly curved wall 21 and at this point the flanges 20 merge

with side walls 22 extending rearwardly from the wall 21. To the side walls 22 are pivotally secured as at 23, an uppermost chute section 24 which has its rear free end adapted to rest on the cross bar 1, when the machine is closed for operation.

It can be seen that when the bottles have been dispensed to such an extent that the last one is on the chute 13, then the upper chute sections 24 and 12 can be swung toward the rear of the machine, that is, after the shell 15 has been lifted, or access has been had through an opening in the shell 15 at the top thereof, on the pivots 19. This exposes the lower section 13. However, should the last bottle be on the second chute 12, then the uppermost chute section 24 is swung forwardly on the pivots 23 to the dotted line position to expose the chute section 12. In this way the supply of bottles can be replenished and build up from one section to the other until the machine is completely charged.

The mechanism for operating the machine includes a shaft 25 which has a finger 26 extending upwardly therefrom and in the path of a plunger 27 of a coin slide generally referred to by numeral 28, and which of course, can be of any design desired, but which is of the type having a slide element for action against the finger 26 to rotate the shaft 25.

Depending from the shaft 25 is an arm 29 which is connected by a pivotal link 30 to a dog 31 swingably mounted as at 32 on one side wall 10.

A tension spring 33 extends between an anchor 34 on the wall 10 and arm 29 and normally maintains the finger in an upwardly disposed position and against the plunger 27 which of course, holds the dog 31 against a ratchet wheel 35. A leg 36 depends from the shaft 25 and serves to block an underlying blade 37 of a dispensing reel generally referred to by numeral 38, when one bottle has been allowed to pass.

The reel consists of a plurality of spokes or the like 39 radiating from a second shaft 40 and to these spokes 39 are secured the blades 37. It is preferable that there are four of these blades radially disposed with respect to the shaft 40 and it is of course, required that the space between the blades be just sufficient to receive one bottle A.

The ratchet wheel 35 is suitably secured to the shaft 40 and has ratchet teeth or projections 41 at the periphery thereof equal in number to the number of blades 37. The ratchet wheel 35 has a hub 42 against which pressure bars 43 bear. These pressure bars 43 serve to snub the action

of the ratchet wheel 35 as it rotates, as the weight of the bottles gravitating on the inclined chute 13 serve to propel the reel 38.

This snubbing means consists of a rod 44 having threaded end portions disposed through apertured ends of the bars 43-43, and this threaded rod has nuts 45 thereon to prevent displacement of the pressure bars 43. The remaining ends of the pressure bars 43-43 are apertured to receive a bolt 46 which has a head 47 bearing against the under side of one of the bars 43. The opposite ends of the bolt 46 has a feedable nut 48 thereon. Interposed between the nut 48 and the upper pressure bar 43 is a compression spring 49, while interposed between the pressure bars 43-43 and on the bolt 46 is a compression spring 50.

It is to be understood that the snubbing means above explained is to be so adjusted that the reel will have a certain degree of freedom to rotate. For instance, when the dog 31 is lifted from the corresponding projection 41, the reel must be allowed to rotate with sufficient rapidity so as to permit the next blade 38 to clear the leg 36 before the leg 36 has lowered to a reel-stopping position.

It can now be seen that a coin is deposited in the coin slider 28 and the mechanism operated to work the plunger 27, which acts against the finger 26. This rotates the shaft 25 and causes the arm 29 to swing upwardly, lifting the dog 31 from behind the adjacent ratchet tooth 41. This permits the first or lowermost bottle to operate the reel 38, but as the leg 36 has been thrown downwardly, it is in the path of the underlying blade 37, so that the reel cannot rotate any more than is required to pass one bottle. When the coin slider 28 is released, the spring 33 retracts the finger 26, returning the plunger 27 of the coin mechanism (not shown in detail) and restoring the mechanism to set position.

The snubbing means shown in Figure 4 of course prevents the reel from operating too rapidly, allowing the bottle to roll out easily. As can be seen in Figure 4, a post 51 projecting from the adjacent wall 10 has the threaded rod 44 carried thereby.

While the foregoing specification sets forth the invention in specific terms, it is to be understood that numerous changes in the shape, size and materials may be resorted to without departing

from the spirit and scope of the invention as claimed hereinafter.

Having described the invention, what is claimed as new is:

- 5 1. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel.
- 10 2. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel.
- 15 3. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.
- 20 4. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.
- 25 5. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.
- 30 6. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.
- 35 7. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.
- 40 8. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.
- 45 9. In a dispensing apparatus, an article impelled reel consisting of a shaft and a plurality of article confining blades extending therefrom, a ratchet wheel carried by the shaft, a second shaft, a finger rising from the second-mentioned shaft, a plunger adapted to be pushed against the finger to rotate the second-mentioned shaft, an arm extending from the second-mentioned shaft, a dog operative against the ratchet wheel to normally prevent rotation of the reel, an operative connection between said arm and said dog whereby upon rotation of said second-mentioned shaft said dog is disengaged from said ratchet wheel and said reel is permitted to rotate, and a leg depending from the second-mentioned shaft and adapted to move into position as said second-mentioned shaft rotates to block the succeeding blade after the reel has rotated a distance equivalent to the width of space between a pair of adjacent blades of said reel, and adjustable snubbing means for the first-mentioned shaft adapted to be adjusted to permit rotation of the reel just free enough to permit engagement of the leg with only the succeeding blade of the reel.

LUTHER D. DENNIS.
